CLAIM

The ornamental design for a machine for preparing beverages, as shown and described.

DESCRIPTION

FIG. 1 is a front, right, and top perspective view of a machine for preparing beverages showing my new design; FIG. 2 is a rear, right, and top perspective view thereof;

FIG. 3 is a top plan view thereof;

FIG. 4 is a front elevation view thereof;

FIG. 5 is a rear elevation view thereof;

FIG. 6 is a left side elevation view thereof; and,

FIG. 7 is a right side elevation view thereof.

The broken lines in the drawings depict portions of the machine for preparing beverages that form no part of the claimed design.
